(57) **CLAIM**

I claim the ornamental design for chair with traction features, as shown and described.

DESCRIPTION

FIG. 1 is a perspective view of a chair with traction features showing my new design;

FIG. 2 is a front view of the chair with traction features thereof;

FIG. 3 is a rear view of the chair with traction features in same position thereof;

FIG. 4 is a left side view of the chair with traction features thereof;

FIG. 5 is a right side view of the chair with traction features thereof;

FIG. 6 is a top view of the chair with traction features thereof; and,

FIG. 7 is a bottom view of the chair with traction features thereof.
